UNITED STATES PATENT OFFICE

EUGENE ROBERTS, OF HASTINGS, NEW YORK, ASSIGNOR TO THE WESTERN STATES MACHINE COMPANY, OF SALT LAKE CITY, UTAH, A CORPORATION OF UTAH

CENTRIFUGAL APPARATUS

Application filed April 10, 1928. Serial No. 268,925.

This invention relates to centrifugal apparatus and is more particularly intended for use in connection with centrifugals used for the purification of sugar or like solid materials from which the liquid content is centrifugally extracted.

In the treatment of brown sugar or partly refined sugar there is frequently used what is known as a self-discharging basket, that is, a centrifugal basket having a steeply inclined frusto-conical bottom with a central discharge opening, the inclination being sufficiently steep to allow that grade of sugar, if properly treated, to slide through the bottom of the basket when the basket comes to rest.

In such baskets, the material to be treated is introduced into the basket when the basket is running at high speed and is naturally thrown against the peripheral wall of the basket by centrifugal force and retained there during the purging and washing operations. This low grade sugar is of such a nature that under proper treatment, it does not pack tightly enough in the basket to prevent its sliding out when, owing to the stopping of the basket, the walled-up sugar is no longer held in place by centrifugal force.

In practice, however, when loading the wet sugar into the basket, particularly if the basket be charged before coming up to proper speed to wall-up the material against the peripheral wall, considerable of the material may fall through the bottom into the conveyor for conducting away the refined material and, by its mixture with said refined material, produce an inferior or unsatisfactory mixture. To guard against this and other troubles, I have provided a self-opening valve constructed and arranged to prevent the accidental escape of material when charging the basket, while being capable of automatically opening when the basket is slowing down to the stopping point preparatory to allowing the discharge of the purified sugar.

To this end my invention comprises, generally speaking, in combination with a centrifugal basket of the self-discharging type, a valve member loosely mounted on the suspension shaft or spindle of the basket to be

slidable thereon so that it may remain seated against the inclined bottom of the basket during the normal or high speed rotation of the basket, while being capable of lifting to uncover the discharge opening in the basket when the machine is slowed down preparatory to allowing the material to discharge through the bottom of the basket.

In the case of the purification of white sugar, this type of basket has not heretofore been practical, because the white sugar packs so firmly into the basket that usually its weight alone is insufficient to dislodge it from the basket when the basket rotation ceases. Heretofore, in the centrifugal treatment of white sugar, or similar material that packs firmly into the basket, it has been customary to use a flat bottom basket and to discharge the sugar by slowly rotating the basket against a discharger plow.

A further feature of my present invention includes means for softening or loosening the outer surface of the sugar wall in contact with the basket, so that this grade of sugar or material may also be automatically discharged without the aid of a plow through its own gravity.

These and other features of my present invention will be particularly described in the following specification and will be defined in the claims hereto annexed.

In the accompanying drawings I have illustrated a simple and convenient embodiment of my invention, in which

Fig. 1 is a side elevation partly in section showing a wellknown type of centrifugal machine provided with my aforesaid improvements.

Fig. 2 is a detail showing in front elevation a part of the connecting mechanism by which a steam-cut-off valve is opened in proper coordination with the centrifugal basket valve mechanism when the power is shut off.

Figures 3 and 4 are details showing, in side elevation, enlarged views of the steam valve controlling mechanism, the former showing the control mechanism in open position of the steam valve, while the latter shows the same mechanism withdrawn from valve operating position to allow the valve to close.

In practice, my improved apparatus may be applied to any wellknown and suitable type of gyratory suspended centrifugal. In Figure 1 I have shown such a centrifugal embracing the perforated centrifugal basket 1 with its frusto-conical steeply inclined bottom 2 having a central discharge opening, in which is secured the usual radial arm-connecting spider 3 which secures the basket to the gyratory suspension spindle or shaft 4^a. This basket shaft or spindle has an enlarged upward extension 4^b supported by radial bearings upon the usual gyratory suspension element which, in a manner wellknown in the art, is mounted in a socket and hanger 5 secured to the overhead horizontal beams 6 that are carried alongside the usual mixer. In the belt driven type of machine a combined driving and brake pulley is secured to the rotary shaft to project around the gyratory centre and receive an external driving belt 8 which passes rearwardly to a driving pulley on the line shaft energized according to usual practice by a clutch under the control of a conveniently located hand lever 9 overhanging the front portion of the machine. The hand lever 9 in the forward position illustrated in Figure 1 is in the centrifugal operating position and, when moved rearwardly, releases the driving clutch and sets the brake inside the pulley 7. All these features thus far described are such common practice and so wellknown in the centrifugal art, that illustration of the details is omitted. I have also omitted showing the interior filter linings of the basket which prevent the escape of the solid particles through the basket wall and bottom, while allowing the liquid to escape through perforations therein.

On the basket spindle 4 is mounted a sleeve or tubular member 12 carrying at its lower end a downward flared or conical extension 13, preferably made of light sheet metal, whose bottom edge is reinforced by a metallic ring 13^a adapted to set against the lower portion of the inclined part of the conical basket bottom, so as to prevent the escape of the contained material from the basket when the valve is seated upon the bottom. At its upper end the loosely fitting sleeve 12 is provided with a flanged collar 14 which overhangs anti-frictional wheel 16 carried in the forked end of the lever 15. This lever is fulcrumed in a bracket 17 mounted on top of the surrounding casing or curb 10 and is provided with an adjustable actuating member, in this case a weight 18, which is slidable along the lever and may be secured in any desired position of adjustment by the set screw 18^a in order to vary the actuating force exerted by it to lift the valve from closing to open position.

Assuming the basket to be empty and at rest, the valve lever will then act to support the basket valve in raised position, the con-

trol lever 9 then being in its rearward position. As the operator starts the machine by pulling the lever 9 forward to operating position, he presses the valve 13 downward until it seats against the basket bottom in basket closing position. When the basket has acquired a moderate speed the frictional clutching action, due to such rotation, establishes sufficient frictional grip between the basket spindle and the surrounding valve rotating therewith to overcome the lifting action of the lever 15, so that the valve remains in closed position, while the material to be treated is admitted to the basket through the usual spout and during the subsequent purging and washing and drying operations of the machine when it is running at normal operative speed.

When the lever 9 is returned to power releasing and brake setting position to allow the machine to slow down preparatory to discharging or unloading, this clutching action is weakened until a point is reached, according to the adjustment of the actuating member 18, where the clutching action is overcome by the weight of the actuating element 18, so that the valve is lifted to open position preparatory to permitting the sugar to slide out of the basket through the bottom when the basket stops rotating. The period intervening between the throwing of the centrifugal control lever 9 to idle position and the actual lifting of the valve before the machine actually stops, will depend upon the adjustment of the lever actuating member 18 and may, of course, be varied by the setting of that member.

To prevent any accidental and unintended opening of the valve, which would allow the basket contents to unload in case the driving power should be accidentally interrupted or cut off, such as by breakage of the driving belt in the case of a belt driven machine, or the failure of current in the case of a motor driven machine, I provide protective means so arranged that the valve remains closed even when the machine is at rest if the starting lever occupies normal operating position.

A rock shaft 35 is mounted in overhead hangers 35^a and has secured to one end an arm 36, whose free end is connected by a link 37 with the valve lifting lever 15, the link member being threaded for extensible adjustment to properly set the device. To said rock shaft is also secured an arm 40 which, at its free end, has a laterally projecting pin 41 projecting through a slot 33 in a rearwardly extending link 32, that is, connected at its forward end with the starting or control lever 9. This is so constructed and proportioned that the pin 41 will be engaged by the rear end of the slot when the starting lever 9 is in operating position and when the valve opening lever 15 is closed position, as indicated in Figure 1. Consequently the rock

shaft 35 is held by the slotted link against clock-wise rotation while the lever 9 is in forward or operating position, thereby preventing the lifting of the inner end of the lever 15 which encases the valve so that at all times, when the lever is in operating position, the valve is positively prevented from lifting.

On the other hand, when the lever is returned either by hand or automatically, as 10 the case may be, to rearward or non-operating position to permit the slowing down and stopping of the machine, the levers 40 and 36 will remain in the same or valve closing position, until such time as the clutching of 15 the valve upon the spindle is reduced to the point where the lifting lever can act to open the valve. The link 32, having been moved rearwardly, affords sufficient play in the slot to permit the pin 41 to move to the rear end 20 of the slot when this valve opening movement occurs.

To render this self-discharging type of basket available for use on white sugar, or on any grade of material, and thus get rid 25 of discharging the material by means of a discharger plow operated by the attendant, I have made provision for loosening the walled-up material by means of a steam jet that is applied for a brief interval between 30 the shifting of the control lever to idle position and the lifting of the valve to open or discharge position and I utilize the valve lifting mechanism to cut off the steam jets automatically after the sugar has been exposed to its softening action for a sufficient 35 period of time to accomplish the desired purpose. This can be readily effected, since there is a substantial interval elapsing after the control lever returns to idle position before 40 the basket slows down enough to allow the valve to lift. Moreover, this interval, as above explained, may be varied by adjustment of the valve lifting means to meet all practical requirements.

45 The loosening of walled-up grains of material is effected by means of plural steam jets issuing from jet nozzles 20 arranged adjacent to the basket and inside the curb on a steam supply pipe 21.

50 The steam supply pipe is provided with a hand cut-off valve 22 and also with an automatically controlled valve 23 of the plunger type. The valve fitting is provided with a fixed bracket 24 in which is pivotally mounted, intermediate of its length, a valve controlling lever 25, which is provided with a counterbalance weight 26 or equivalent device for normally closing and keeping this valve closed. The upper end of the valve 55 lever 25 is arranged in substantial alignment with the link 32. This link carries a pawl 30 which is pivoted to the link at 31 and extends rearwardly with its rear end dropped to the plane of the pivotal centre 31. This 60 pawl, intermediate of its ends, rests loosely

upon the upper or free end of the arm 40, which arm is provided with a projecting nose 42 which performs no function when the arm 40 is in valve closing position, but which acts when the arm 40 swings to valve opening position to lift the free end of the latch or pawl 30 out of engagement with the upper end of the steam valve controlling lever 25.

Parts, as shown in Figure 1, occupy the 70 normal position when the centrifugal is running with the control lever in forward position, the basket valve closed and the steam valve also closed by its actuating weight 26. When the lever 9 is moved rearwardly to idle position, the pawl 30 then in engagement with the upper end of the steam controlling valve lever 25 forces the valve lever 25 rearwardly on its fulcrum, the thrust being in line with the pivotal centre 31 of the pawl or latch. This opens the steam valve and holds it in open position until the basket has slowed down sufficiently to allow the basket valve lifting mechanism to operate, thus bringing the nose 42 of the arm 40 into lifting contact with the underside of the latch 30, thereby 75 lifting the free end of said latch above and out of engagement with the adjacent end of the steam valve lever which allows the actuating member 26 to close the steam valve to 80 cut off the steam supply.

A few seconds later the basket stops and the sugar automatically discharges through the uncovered bottom discharge opening. When the attendant is ready to start and reload the machine, he throws the lever 9 forward to operating position and thereby, through the slotted link 32, moves the arm 40 and the co-acting valve mechanism to valve closing position, so that the valve is closed and kept closed before the centrifugal acquires speed enough to produce clutching action to interfere with the closing of 90 the valve.

100 It will therefore be seen that as soon as the centrifugal controlling lever returns to idle position to slow down and stop the basket, but while the basket is still revolving, the steam jets are directed against the perforated wall of the basket to loosen the sugar. This action continues for a few seconds when 105 the further slowing down of the machine, according to the adjustment of the counterweight 18 allows the lifting mechanism to open the valve and at the same time cut off the steam jets.

110 The advantage of connecting the basket valve closing mechanism with the control lever is that it avoids any trouble due to negligence or forgetfulness of the workman to close the valve and, also prevents the un-purified sugar from discharging into the conveyor beneath, into which only purified sugar is intended to be discharged, and therefore prevents mingling the dirty sugar 115 with the purified sugar besides preventing 120 125 130

the mingling of the untreated sugar in case the basket is loaded before the machine is rotating rapidly enough to cause the material to wall-up against the basket wall.

6. What I claim is:

1. In a sugar centrifugal apparatus the combination with a suspended gyratory centrifugal whose basket has a frusto-conical bottom with a central discharge opening, a bottom closing valve slidably mounted on the basket suspending shaft, and self-acting means for lifting said valve from bottom closing position when the centrifugal has slowed down to a predetermined speed.
10. 2. In a sugar centrifugal apparatus the combination with a centrifugal basket having a steeply inclined frusto-conical bottom with a central discharge opening, a bottom closing valve slidably mounted on the basket shaft to seat against the bottom and prevent escape of the contained material through the bottom opening, and valve lifting means normally rendered inoperative through the rotation of the basket at operating speed, while 20 acting when the basket rotates at low speed to lift the valve and uncover the discharge opening preparatory to allowing the contained material to discharge of its own weight through the bottom of the basket.
25. 3. A gyratory centrifugal whose suspended basket has a steeply inclined bottom provided with a central discharge opening combined with a hollow valve of substantially conical form slidably mounted on the suspension shaft to close said bottom opening against the escape of the contained material, and a self-acting valve-actuating member operating to lift said valve to open position when the centrifugal has slowed down to a 30 predetermined speed.
40. 4. A gyratory centrifugal whose suspended basket has a steeply inclined bottom with a central discharge opening, combined with a hollow valve of substantially conical form having an upwardly extending tubular sleeve loosely engaging the basket suspending shaft to permit the valve to slide freely upon said shaft when the machine is rotating at a relatively low speed, while acting through the 45 clutching engagement produced by rotation at normal operating speed to frictionally prevent the movement of said valve on the shaft substantially as described.
50. 5. A gyratory centrifugal whose suspended basket has a steeply inclined bottom provided with a central discharge opening, combined with a bottom closing valve slidably mounted on the basket suspending shaft, self-acting means operating to lift said valve to open 55 position when the machine has slowed down to a predetermined speed, said valve lifting means being adjustable to permit it to become operative at different predetermined speeds of the centrifugal.
60. 6. The combination with a suspended 65

gyratory centrifugal whose basket has a steeply inclined bottom with a central discharge opening, of a closure valve for said opening, self-acting means for lifting said valve from its seat to open position when the centrifugal has slowed down below a predetermined speed, and means cooperatively associated with said valve to loosen the walled up material in the basket to assist its discharge therefrom.

70. 7. The combination with a gyratory centrifugal whose suspended basket has a steeply inclined bottom provided with a central discharge opening, and a controlling lever by means of which the centrifugal is started and stopped, of a bottom closing valve, self-acting means for lifting said valve to open position when the centrifugal has slowed down to a predetermined speed, said valve lifting means being interconnected with the starting lever to prevent the lifting of the valve when the starting lever is in normal operating position.

75. 8. A self-discharging centrifugal embracing in combination with a suspended open bottom basket and a control element by which the centrifugal is started and stopped, a bottom closing valve means for lifting the valve from closing position, said means becoming 80 operative only when the basket has slowed down to a predetermined speed, and means for preventing the lifting of the valve when the control element is in normal centrifugal operating position.

85. 9. In combination with a sugar centrifugal and means controlling the starting and stopping thereof, a steam supply pipe constructed and arranged to deliver steam jets against the outside of the centrifugal basket, means acting to open said valve when the controlling means is set to stopping position and means acting after the centrifugal has slowed down to allow the cut-off valve to return to closed position.

90. 10. The combination with a sugar centrifugal having an open bottom basket and a control lever for effecting the starting and stopping of the centrifugal, a bottom-closing valve, means for directing jets of steam against the basket, a steam cut-off valve, the starting lever, the bottom-closing valve, and the steam cut-off valve being operatively co-ordinated to effect the opening of the steam valve through the agency of the control lever moving to stopping position and to close the cut-off when the bottom-closing valve moves to open position.

95. 11. The combination with a sugar centrifugal having an open bottom basket and a control lever for effecting the starting and stopping of the centrifugal, a bottom-closing valve, means for directing steam against the basket to loosen the material therein, a steam cut-off valve, means acting under the control 100 of the starting lever to open said cut-off

valve and, after proper sequence, closing said valve and allowing the bottom-closing valve to move to open position when the centrifugal has slowed down to a predetermined speed, 5 said controlling means acting to reset the bottom valve to closed position when the starting lever is shifted to operating position.

12. The combination with a centrifugal having an open bottom basket and a starting 10 and stopping lever, means for directing steam against said basket to loosen the material therein, a steam cut-off valve actuated by a counterbalance lever to open position when the centrifugal has slowed down to a 15 predetermined speed, a link, a pawl actuated thereby to open the cut-off valve when the control lever is shifted to non-operating position, said link and said pawl and said counterbalance lever being co-ordinated to effect 20 the opening of the cut-off valve and the subsequent opening of the bottom-closing valve when the control lever is shifted to non-operating position, while causing the closing of the bottom-closing valve when the lever is 25 moved to operating position.

13. A centrifugal apparatus embracing in combination a gyratory centrifugal having an open bottom basket and a control lever for starting and stopping the centrifugal, means 30 for directing steam against the centrifugal basket to loosen the material therein, a steam cut-off valve, means for raising said bottom-closing valve to open position when the centrifugal has slowed down to a predetermined. 35 speed, a connecting link, a pawl actuated thereby for opening said steam cut-off valve, a rock arm actuated when the control lever is in non-operating position to release said pawl from actuating position when the bottom-closing valve moves to open position. 40

In witness whereof, I have subscribed the above specification.

EUGENE ROBERTS.
